UNITED STATES PATENT OFFICE

HOMER G. KELLOGG, OF DETROIT, MICHIGAN, ASSIGNOR TO MOTOR PRODUCTS CORPORATION, OF DETROIT, MICHIGAN, A CORPORATION OF NEW YORK

HINGE

Application filed October 13, 1930. Serial No. 488,487.

This invention relates to hinges and more particularly to improvements in the construction thereof tending to improve and render the same more efficient.

The present invention constitutes a modification of the former construction illustrated, described, and claimed in my prior Patent No. 1,666,211 dated April 17, 1928.

The several objects, advantages and novel details of this invention will be made more apparent as this description proceeds, especially when considered in connection with the accompanying drawing wherein:

Figure 1 is a vertical sectional view showing one application of my invention, the same being shown in connection with portions of a frame and windshield;

Figure 2 is an enlarged sectional view through the hinge with the hinge parts in closed position, and

Figure 3 is a similar view with the hinge parts in open position.

At the outset it should be understood that while this invention is illustrated in the drawing hereof as the means for pivotally connecting a windshield to a frame member, that the invention may be employed with equal facility in many other ways. For instance, this type of hinge may be employed to great advantage as a hood hinge for the hoods of motor vehicles and the like. Therefore, the illustrative embodiment of this invention in so far as its particular application is concerned should not be considered as limiting the invention in any manner whatsoever.

In Figure 1 there is illustrated a hinge comprising hinge parts 10 and 11 each of which consists of a metal strip or a length equal to the desired length of the hinge. The hinge part 10 is connected in any suitable manner to a stationary frame part 12 while the hinge part 11 is connected to the movable frame part 13 of a windshield. The frame member 13 is herein illustrated as being provided with a groove 14 to receive the windshield glass 15.

The outer hinge part 10 is provided with a bead 16 substantially semi-circular in cross-section which bead terminates in an inturned

edge portion 17. The inner hinge part 11 is provided with a companion interfitting semi-circular bead 18 which bead terminates in an inturned edge portion 19.

As mentioned, the interfitting beads 16 and 18 are semi-circular in cross-section and in the closed position of the hinge parts, the beads embrace one another as clearly illustrated in Figure 2.

The arcuate portions of the beads 16 and 18 are substantially described from a center which may be considered located at the point C which as will be noted is located a short distance from the extremity or end portion of inturned edge 19 of the inner hinge member 11. Thus the two hinge parts pivot one upon the other for movement as will be obvious.

As shown in Figure 2, the inturned edge 17 of the outer hinge part 10 extends beyond and over the extremity of the inturned edge 19 of the inner hinge part. As also clearly illustrated, the extremity of the inturned edge 17 fits between the end of the inturned part 19 and the interior surface of the bead 18 of the inner hinge part.

The extremity 20 of the inturned edge 17 is curved, the arc of this curved portion being struck from the aforesaid center C. This provides opposed curved bearing surfaces 21 and 22, arcuate in shape on an arc struck from the center C. The outer surface or end 23 of the inturned edge 19 is also rounded or curved on an arc struck from the center C. Thus the curved or rounded end 23 of the inturned edge 19 engages the curved bearing surface 22 of the inturned edge 18 of the outer hinge part, whereas the outer curved surface or bearing surface 21 of this inturned edge portion 17 engages the interior surface of the bead 18 of the inner hinge part 11 and constitutes a bearing therefor during the relative movement of the hinge parts.

As will be noted, the distance or space between the rounded end surface 23 and the interior surface of the bead 18 is substantially equal to the thickness of the hinge part 10 and particularly of the extremity 20 thereof. Thus, this extremity fits between these two surfaces and acts as a bearing support

for both, the bearing surfaces thus provided being opposite or opposed one to the other.

As a consequence of this structure, the hinge parts are held firmly in contact with one another irrespective of the relative angular position of the hinge parts. In the closed position of the hinge, the interfitting beads 16 and 18 embrace one another substantially throughout their entire surfaces and in the extreme open position of the parts illustrated in Figure 3, the outer bearing surface 21 of the extremity 20 is in contact practically throughout with the interior surface of the bead 18 of the hinge part 11.

15 A comparison of Figures 2 and 3 will indicate clearly that the hinge part 11 may be swung relatively to the hinge part 10 through an angle of approximately 170° , the parts still remaining in intimate non-rattling contact throughout all of this relative movement.

Various modifications may suggest themselves to those skilled in this art and to this end reservation is made to make such changes 25 as may come within the purview of the accompanying claims.

What I claim as my invention is:

1. A hinge comprising a pair of hinge parts each having a bead formed therein for interfitting pivotal engagement, said beads each terminating in an inturned edge, the inturned edge of the outer bead being extended and shaped to constitute a bearing surface for the end of the inturned edge of the inner bead 35 and for the inner surface of the inner bead.

2. A hinge comprising a pair of hinge parts each having a bead formed therein for interfitting pivotal engagement, said beads each terminating in an inturned edge, the extremity of the outer inturned edge extending between and engaging respectively the extremity of the inner inturned edge and the interior surface of the inner bead.

3. A hinge comprising a pair of hinge parts each having a bead formed therein for interfitting pivotal engagement, said beads each terminating in an inturned edge, the extremity of the outer inturned edge having a bearing engagement respectively with the inturned edge and bead of the inner hinge part.

4. A hinge comprising a pair of hinge parts each having a bead formed therein for interfitting pivotal engagement, said beads each terminating in an inturned edge, the inturned edge of the outer bead extending beyond and over the inner inturned edge and having a bearing engagement therewith and with the interior of the inner bead.

In testimony whereof I affix my signature.
60 HOMER G. KELLOGG.
